UNITED STATES PATENT OFFICE.

WALTER T. GORTON, OF THE UNITED STATES ARMY, SPRINGFIELD, MASSACHUSETTS.

SEAR MECHANISM FOR GUNS.

Application filed July 11, 1924. Serial No. 725,442.

(GRANTED UNDER THE ACT OF MARCH 3, 1883; 22 STAT. L. 625.)

The subject of this invention is a sear mechanism for guns.

In mounting machine guns on aircraft, it is customary to operate the gun by means of a trigger motor adapted for synchronized fire and mounted exterior to the gun, while provision may be made in the gun casing for attaching the trigger motor to either side of the gun to be readily interchangeable with a hand trigger. Consequently, the slide for releasing the sear from the firing pin must be operable from either side of the gun and is ordinarily so constructed that a considerable thrust is required to release the sear.

15 This condition not only necessitates an exceedingly strong construction in the synchronizing gear, results in the use of an appreciable amount of power, occasional breakage and frequent loss of adjustment, but is 20 not desirable when the gun is operated by a hand grip on account of the amount of trigger pull which would have to be exerted.

A considerable advantage, therefore, accrues when a much easier sear release is 25 provided but such an improvement must be effected without increasing the probability of accidental release of the sear due to faulty holding. The usual procedure has been to have the sear engage the firing pin at an 30 angle of 90° and to depend upon the sear being held in engagement by action of a spring. Release of the sear has been effected by a sliding member which cams the sear out of engagement with the firing pin when 35 thrust inward by the action of the trigger, while reengagement of the sear and return movement of the sear slide have been accomplished by a spring.

My invention resides in the changing of 40 the sear engaging surfaces of the firing pin and the corresponding surfaces of the sear to a 45° plane with respect to the axis of the firing pin to release the sear upon application of a relatively light thrust, and in designing the sear and sear slide so that the 45 action of the sear slide will be to positively lock the sear in cocked position, and to permit the firing pin to disengage the sear at the proper point in movement of the sear slide. I, also, construct the sear slide and 50 its spring so that they may be reversed, the spring being then mounted on the opposite side of the bolt, to permit of operation by the trip element located on either side of the 55 gun.

To these and other ends, my invention consists in the construction, arrangement, and combination of elements, described herein-after and pointed out in the claims forming a part of this specification. 60

A practical embodiment of my invention is illustrated in the accompanying drawings, in which,

Fig. 1 is a top plan view of a gun broken to show the arrangement of trip and sear 65 slide;

Fig. 2 is a longitudinal sectional view showing the sear disengaged from the firing pin and the slide in unlocked position.

Fig. 3 is a sectional view taken on the line 70 3—3 of Fig. 2;

Fig. 4 is a plan view of the slide;

Fig. 5 is a view of the slide in elevation;

Fig. 6 is a perspective of the sear;

Fig. 7 is a sectional view taken on the line 75 7—7 of Fig. 6;

Fig. 8 is a sectional view taken on line 8—8 of Fig. 6; and

Fig. 9 is a longitudinal sectional view of 80 the firing pin.

Referring to the drawings by numerals of reference:

10 indicates the side plates of the machine gun between which reciprocates the bolt 11, formed with a longitudinal bore in which is 85 reciprocably mounted a firing pin 12, and pivotally carrying the usual cocking lever 13. The firing pin is held in cocked position by a sear 14, which slides vertically in slots 11', cut in the bolt and the lower end 90 of which seats in a groove 12' cut transversely in the upper surface of the firing pin adjacent its rear end.

The sear is depressed to its lowermost position by a sear spring 15, mounted on a 95 pin 16, located in a suitable aperture in the bolt and passing through aligning slots in the firing pin to form the rear abutment for the firing pin spring 17. The pin 16 is beveled at its point to facilitate insertion in 100 the slots in the firing pin and seats in a recess formed in the bolt beneath the firing pin. The lower portion of the sear 14 is formed with an outstanding lug 18 beveled on its under surface at an angle of 45° or 105 any angle less than 90°, to co-act with a correspondingly beveled surface 19 in the groove 12' of the firing pin.

A slide 20, mounted transversely of the bolt and having a sliding fit in a groove 110

formed therein, rides on the lug 18 of the sear and is normally projected in line with a trip element by a spring 21, mounted on a pin 22, carried by the bolt and recessed 5 for engagement by the sear spring pin 16 as clearly shown in Fig. 2, whereby to prevent lateral displacement of the pin. One end of the slide is recessed as at 20' to form a seat for the slide spring 21, while the under 10 portion is cut away as at 22' to form a groove which is slightly wider than the lug 18 and into which the lug is permitted to rise when the slide has been actuated by the trip element. The slide is further formed with 15 opposite projections 23, which are so positioned with respect to the groove 22' that one of them will engage one side of the sear and limit the lateral movement of the slide and the action of the slide spring at a point 20 where the groove 22 will be to one side of the lug 18. The slide is so formed that it may be reversed for operation from either side of the gun.

Upon recoil of the bolt, the cocking lever 25 13 retracts the firing pin against the tension of the firing pin spring 17 until the sear under force of its spring is depressed into the groove 12' of the firing pin. When the sear has been depressed clear of the 30 groove 22' in the slide, the slide will be free to be moved laterally by its spring, the lowermost portion in the slide riding on the lug 18 of the sear and positively locking the sear and firing pin in cocked position. 35 When the slide is actuated by the trip element, the groove 22' of the slide will be positioned opposite the lug 18 of the sear, when by reason of the beveled surfaces of the lug 18 and groove 12' of the firing pin, 40 the firing pin under the influence of the firing pin spring will cam the sear out of engagement and into the groove 22' and be released to firing position.

Removably mounted on either of the side 45 plates is a trip housing 24, which is channeled to enclose a trip element 25 reciprocably mounted within the housing adjacent the side plate and normally maintained in idle position by a spring 26. The trip 50 25 is operatively engaged with a trigger 27 by means of a lug 28 on its rear end while its front end is terminated by a T-head, one wing of which is formed with a beveled face extending through an aperture in the side 55 plate and adapted to actuate the slide 20, while the other wing is adapted to seat the forward end of the spring 26.

While in the foregoing there has been 60 illustrated and described such combination and arrangement of elements as constitute the preferred embodiment of my invention, it is nevertheless desired to emphasize the fact that interpretation of the invention should only be conclusive when made in the 65 light of the subjoined claims.

I claim:

1. A machine gun embodying a bolt, a firing pin, a firing pin spring, a cocking lever carried by the bolt and adapted to retract the firing pin, a sear slidably mounted on the bolt, a spring engaging the sear, a pin carried by the bolt and extending through the firing pin for retaining the sear spring and the firing pin spring, a slide adapted to ride on a portion of the sear, said slide 75 formed with a groove on its lower side, a stop formed on the slide and adapted to engage the sear, a spring engaging the slide, a pin carried by the bolt for retaining said spring, said pin formed with a recess to receive the first mentioned pin, and means for actuating the slide.

2. A machine gun embodying a bolt, a firing pin, a firing pin spring, a cocking lever carried by the bolt and adapted to 85 retract the firing pin, a sear slidably mounted on the bolt, a spring engaging the sear, means for retaining both the sear spring and firing pin spring, a slide adapted to ride on a portion of the sear, said slide formed 90 with a groove on its lower side, a stop formed on the slide and adapted to engage the sear, a spring engaging the slide, a pin carried by the bolt for retaining said spring, said pin formed with a recess to receive the sear 95 spring retaining means, and means for actuating the slide.

3. A machine gun embodying a bolt, a firing pin, a firing pin spring, a cocking lever carried by the bolt and adapted to 100 retract the firing pin, a sear slidably mounted on the bolt, a spring engaging the sear, a pin carried by the bolt and extending through the firing pin for retaining both the sear 105 spring and firing pin spring, a slide adapted to ride on a portion of the sear, said slide formed with a groove on its lower side, stops 110 formed on the slide and adapted to engage the sear, means for normally forcing one of the stops against the sear, and means for 115 actuating the slide.

4. A machine gun embodying a bolt, a firing pin, a firing pin spring, a cocking lever carried by the bolt and engageable with the firing pin, a sear slidably mounted 115 on the bolt, said sear formed with a lug, means for depressing the sear into engagement with the firing pin, a slide adapted to ride on the lug of the sear, said slide formed with a groove on its lower side, a stop 120 formed on the slide and adapted to engage the sear, means for normally positioning the slide so that the lug of the sear will be out of line with the groove of the slide, and means for aligning the lug and groove of 125 the slide.

5. A machine gun embodying a bolt, a firing pin carried by the bolt, said firing pin formed with a groove having a beveled rear wall, means for cocking the firing pin, a 130

- sear slidably mounted on the bolt, a lug formed at the bottom of the sear and having its under surface beveled, means for normally depressing the lug into the groove of the firing pin, means adapted to ride on the lug for locking the firing pin in cocked position, said means being formed with a groove, means for normally maintaining the aforesaid means in locking position, means for positioning the locking means in unlocked relation to the sear, and means carried by the firing pin for automatically actuating the firing pin when the locking means are in unlocked relation to the sear.
6. In a machine gun, the combination with a bolt, a firing pin and a cocking lever, of a sear adapted to engage the firing pin by a surface less than a right angle, means for depressing the sear into engagement with the firing pin, reversible means engageable with the sear for normally locking the sear and firing pin in engagement, said means being formed to provide a clearance for the sear when in unlocked relation to the sear, means for positioning the aforesaid means in unlocked relation to the sear, and means for automatically actuating the firing pin when the locking means are moved to unlocked position.
7. In a machine gun, the combination with a bolt, a firing pin and a cocking lever, of means adapted to engage the firing pin when the same is retracted, a reversible slide engageable with the aforesaid means for normally locking the same in firing pin engagement, said slide being formed to provide clearance for said means when in unlocked relation thereto, means for moving the slide to unlocked position, and means for automatically releasing the firing pin when the slide is moved to unlocked position.
8. In a machine gun, the combination with a bolt, a firing pin and a cocking lever, of means adapted to normally engage the firing pin when the same is retracted, reversible means for locking the aforesaid means in firing pin engagement said means being adapted to be automatically moved into lock-
- ing position, and manually moved to unlocking position, and means for automatically releasing the firing pin.
9. In a machine gun unit, a bolt, a firing pin reciprocally mounted within the bolt, means for cocking the firing pin, a sear engageable with the firing pin to hold it in cocked position, a reversible slide for locking the sear, means for actuating the slide, and means for automatically releasing the firing pin.
10. In a machine gun unit, including a sear, a reversible sear locking slide formed with opposed stops, and a slide operating mechanism securable on either side of the gun.
11. In a machine gun unit, a sear, a slide engageable with the sear, a stop formed on the slide and adapted to engage the sear, said slide having a groove positioned with respect to the stop so that the groove will be out of line with the sear when the stop engages the sear, and means for actuating the slide.
12. In a machine gun unit, a bolt, a firing pin reciprocally mounted within the bolt, a spring carried by the firing pin, means for cocking the firing pin, a sear engageable with the firing pin to hold it in cocked position, a sear spring, a pin for retaining the sear spring and firing pin spring, a slide, a slide spring and a pin for retaining the slide spring, said pin formed with a recess to receive the first mentioned pin, whereby to prevent lateral displacement.
13. In a machine gun unit, a bolt, a firing pin reciprocally mounted within the bolt, means for cocking the firing pin, a sear engageable with the firing pin to hold it in cocked position, and a member slidably in either direction transversely of the bolt to lock the sear.
14. The combination with a breech bolt, of a sear carried by the bolt, and a sear lock, said lock reversible whereby it may be operated in reversed directions to release the sear.

WALTER T. GORTON.
